ELECTRICAL FOOD WARMER

Malen Z. Tevolitz, Monroe, Conn., and Manfred K. Hege-
mann, Nyack, N.Y., assignors to Sperry Rand Corpo-
ration, New York, N.Y.

Filed May 28, 1970, Ser. No. 23,194

Term of patent 14 years

Int. Cl. D7—02

U.S. Cl. D44—1

Fig. 1.

Fig. 2.

Fig. 3.

Fig. 4.

Fig. 5.

FIG. 1 is a front perspective view of an electrical food warmer showing my new design;

FIG. 2 is a top plan view thereof;

FIG. 3 is a rear elevational view thereof;

FIG. 4 is a side elevational view thereof as seen from the left of FIG. 3; and

FIG. 5 is a bottom view thereof.

We claim:

The ornamental design for an electrical food warmer, substantially as shown.
